UNITED STATES PATENT OFFICE

2,565,766

AUTOMATIC MERCHANDISING MACHINE

Christian Gabrielsen and Hrand Vorperian,
Whippany, N. J., assignors to Rowe Manufacturing Co., Inc., Whippany, N. J., a corporation of New York

Application September 8, 1949, Serial No. 114,614

8 Claims. (Cl. 312—94)

1

Our invention relates to an automatic merchandising machine and more particularly to a coin controlled machine adapted to vend candy bars and other merchandise in a simple, convenient and expeditious manner.

Due to the universal demand for cigarettes, there are a great many cigarette vending machines of various types, all of which revolve around the principle of stacking cigarettes. Cigarette packages are regular in shape and are usually wrapped in cellophane, so they lend themselves very readily to this form of machine.

A great many articles, however, cannot be stacked due to their composition or shape, and thus require special constructions in order to be able to vend them through an automatic merchandising machine. Candy bars, for example, are not only irregular in shape, but will become deformed or spoiled if it were attempted to stack one candy bar on top of another. Due to the necessity of making special provision for the storing of articles of this type, the capacity of candy vending machines, for example, has been limited as compared with cigarette machines. The result is that they must be serviced very frequently, especially if situated in a location where there is a large demand for candy bars. This tends to make the operation of machines of this type uneconomical.

One object of our invention is to provide an automatic merchandising machine adapted to vend articles which cannot be stacked, in a simple, convenient and expeditious manner.

Another object of our invention is to provide an automatic merchandising machine for candy bars or the like having a large capacity.

Another object of our invention is to provide an automatic merchandising machine which is flexible in design, simple and inexpensive in construction, and certain in its operation.

Other and further objects of our invention will appear from the following description.

In the accompanying drawings which form part of the instant specification and which are to be read in conjunction therewith, and in which like reference numerals are used to indicate like parts in the various views:

Figure 1 is a side elevation of an automatic merchandising machine containing one embodiment of our invention.

Figure 2 is a fragmentary front view taken along the line 2—2 of Figure 1.

Figure 3 is an elevation showing a portion of the coin register, drawn on an enlarged scale, taken along the line 3—3 of Figure 2.

Figure 4 is a fragmentary elevation drawn on an enlarged scale, taken along the line 4—4 of Figure 2.

Figure 5 is a perspective view with parts in section, drawn on an enlarged scale, taken along the line 5—5 of Figure 2.

Figure 6 is a sectional view taken along the plane 6—6 of Figure 5.

Figure 7 is a sectional view taken along the plane 7—7 of Figure 5.

Figure 8 is a perspective view similar to Figure 5, showing a modified construction containing another embodiment of our invention.

In general our invention contemplates the provision of a plurality of pivoted shelves each formed with a crank rotatable with the shelf. A flexible steel member such as a steel tape is adapted to contact the shelf cranks to hold them in a horizontal position, in which position the merchandise to be vended is supported by the shelf. Means are provided for progressing the steel tape successively to free it from contact with the shelf cranks such that the weight of the shelf and its merchandise will permit the shelf to pivot to dump the merchandise being vended to a chute for delivery to the purchaser. A plurality of columns of merchandise shelves are provided, each equipped with its own movable shelf supporting member. Operating means are provided for advancing the shelf supporting member successively to free the shelves. An operating bar normally locked by a coin mechanism prevents the actuation of the operating member. Upon the deposit of coins of the right denomination the operating bar is freed to permit the actuating member to free a shelf. Merchandise is selected by pulling a knob opposite a respective column.

The coin register used with our machine may be of any suitable type, but we prefer to use, and have shown our machine with the coin register shown in copending application of Christian Gabrielsen, Serial No. 768,997. This coin register is adapted to vend for various prices and will take any combination of nickels and dimes, as well as a quarter, and give change on a fifteen cent purchase of a nickel for two dimes, and ten cents with a deposit of a quarter.

More particularly referring now to the drawings, our automatic merchandising machine comprises a base member 10 to which are secured a pair of side frame members 12 positioned at each end of the base. Between the side members 12 and parallel thereto we provide a plurality of vertically extending partitions 14 extending be-

tween the front vertically extending frame members 16 and rear vertically extending frame members 18, as can readily be seen by reference to Figure 5. The shelves 20 are supported by wire members 22 which are secured to the shelves, as can readily be seen by reference to Figure 5. One end of the wire member is pivotally positioned in rear frame member 18 and the other end of the wire member 22 is pivoted in the front frame member 16. The wire is bent to the form of a U 24 intermediate its ends to form a shelf supporting portion. The front end of the wire which passes through the support 16 is formed with a crank 26, the purpose of which will be pointed out more fully hereinafter.

Carried by the base 10 we provide a housing 28 formed with a slot 30 through which an operating bar 32 passes. Any suitable parallel motion arrangement, such as gear segments 31 meshing with a suitable rack (not shown), is provided so that the operating bar will reciprocate in the slot 30 parallel to itself. A plurality of pull rods 34 provided with knobs 36 are mounted adjacent each of the respective columns of the machine. A sliding cam arrangement positioned in the housing 40 is provided, such that when one of the knobs 36 is pulled the other knobs will be locked. The arrangement is well known to the art, and is operated by cams 41, one of which is carried by each of the pull rods 34 adapted to cam a plurality of members to block the operation of all the other pull rods 34 when one of the pull rods is operated. Each of the pull rods 34 is secured to a reciprocating member 42 shown in Figures 5 and 7, adapted to engage the operating bar 32 whenever any rod 34 is pulled. Pivotally secured to the lower end of member 42 we provide a pivoted member 44 adapted to be cammed upwardly by a cam plate 46 whenever the pull rod 34 is moved to the left, as shown in Figure 7, to embrace the operating rod 32. The cam plate 46 is provided with a slot 48 through which the lower end 50 of the member 42 passes to prevent rotation around the axis of the pull rod 34. When the member 44 is swung upwardly by the cam plate 46 it will embrace the operating bar so that it will be carried back along with the member 34 on the return motion. A double cam member 52 is secured to the member 42 for reciprocation therewith. This member is shown in perspective in Figure 5 and carries a lower cam plate 54 and an upper cam plate 56. The upper cam plate 56 is formed integrally with the member 52. The lower cam plate 54 is pivotally mounted around pivot pin 58 carried by the member 52. A vertically positioned reciprocating member 60 is mounted adjacent the front of each column, as can readily be seen by reference to Figures 5, 6 and 7. This member is normally urged upwardly by a spring 62 and is provided with a plurality of lugs 64 which taper upwardly. The lower end of the reciprocating member 60 is provided with a pin 66 carrying a roller 68. The roller normally engages the lower surface of the upper inclined cam 56, as shown in Figure 5.

Referring now to Figure 1, a bell crank 70 is pivoted about pin 72 carried by the side member 12. A spring 74 normally urges the bell crank to rotate in a clockwise direction. The bell crank is provided with an upper pin 76 and a lower pin 78 which are adapted to engage surfaces formed upon a cam 80 shown in dotted lines in Figure 1 and in full lines in Figure 3. A pin 82 passes through a slot 84 formed in a link 86. The end of link 86 is pivoted to the lower end of an arm

88 which is pivotally mounted to the side member 12 by means of pin 90. The other end of link 86 is secured to the operating bar 32 which carries at this point a pawl 92. A rack 94 is carried by the plunger housing 28. Whenever a knob 36 is operated the operating bar 32 will move to the left carrying with it the link 86. The slot 84 permits a limited amount of motion of the link before action upon the cam 70. The amplitude of this motion is insufficient to permit the toe 96 of the pawl 92 to engage the first tooth 98 of the rack 94. The arrangement is such that once the vending cycle is started after correct coins are positioned in the coin register, the toe 96 will engage the first tooth 98 and prevent return motion of the operating bar until the vending cycle is completed. The movement of the operating bar will cause the link 86 to move to the left, as viewed in Figure 1, engaging the pin 82 and rotating the bell crank in a counterclockwise direction.

The other arm of the bell crank carries a pin 100 to which is pivotally secured a link 102. The rocking of the bell crank in a counterclockwise direction will raise the link 102, the upper end of which is positioned in a slot 104 formed in a flange 106 carried by a member 108 supported by the side member 12 of the frame. A locking lever 110 is pivoted about a pin 112 carried by the bracket 108. A spring 114 is secured to the upper end of the locking lever 110 by means of a pin 116 and is adapted to rotate the locking lever in a clockwise direction. The lower end of the locking lever is provided with a toe 118 extending through an opening 120 formed in the member 108. A flange 122 is formed at the side of the locking lever and is adapted to be engaged by the lower end of an unlocking lever 124 which is pivoted about a pin 126. When the locking lever 110 is in the position shown in Figure 1, the upper end 101 of the link 102 will butt against the toe 118 of the locking lever and prevent further rotation of the bell crank 70. This is reached before the toe 96 of the pawl 92 engages the first tooth 98 of the rack 94. One of the coin register slides 130, when freed by coins, is adapted to move to the left as viewed in Figure 1, to pivot the unlocking lever 124 in a counterclockwise direction causing the lower end of the unlocking lever 124 to move to the right acting against the flange 122 of the locking lever, pivoting the locking lever to rotate in a counterclockwise direction and carrying the locking lug 118 to the right free of the end 101 of the link 102. When this occurs the knob 36 may be pulled through its full stroke rotating the bell crank 70 in a counterclockwise direction, as viewed in Figure 1, and in a clockwise direction as viewed in Figure 3, in which figure only the pins 76 and 78 carried by the bell crank are shown.

Referring now to Figure 3, whenever knob 36 is pulled the pins 76 and 78 will rotate the cam 80 about its pivot 132 in a clockwise direction as shown by the arrow. When there are no coins in the coin register or insufficient coins are present to free one of the register slides the locking arm 101 butts up against the flange 118 on the locking lever 110 and the motion stops. The limited rotation of the cam 80, however, will rock the bell crank 134 which is pivoted about pivot 136 in a counterclockwise direction, pulling the link 138 which is pivotally connected by pivot pin 140 to the bell crank 134, to the left against the action of spring 142. A lever 144 is pivoted about pin 146 and its upper end is connected to a link 148 by means of pivot pin 150. The lower end

of lever 144 is provided with a pin 152 which seats in a reentrant portion 154 formed in the link 138 so that as the link 138 moves to the left it will rotate the lever 144 in a clockwise direction pulling the link 148 to the right. Link 148 is connected to a pivoted lever 156 by pivot pin 158. The lower end of lever 156 which is pivotally mounted adjacent its upper end (not shown) is provided with a roller 160 which bears against an inclined cam surface 162 formed at the end of lever 164 pivoted about a pin 166. A spring 168 urges the cam portion 162 downwardly and tends to swing the lever 156 to the left as viewed in Figure 3. As the link 148 moves to the right it will swing the lever 156 to the right against the action of the cam lever just described. A link 170 is secured to the lever 156 by means of the pin 172 so that it will be moved to the right when the lever 156 swings to the right. The link 170 has a depending portion 174 which is connected by spring 176 to a plurality of links 178, each of which is connected to a pair of links 180 which are connected in turn to the coin register slide 130. The movement of the link 170 to the right tends to move the coin register slides to the right, as viewed in Figure 3, and to the left as viewed in Figure 1. When an insufficient number of coins is in the coin register to free one of the slides the slides lock and tension is placed on the spring 176 and the operation of the machine is stopped by the locking lever. A bell crank 182 pivoted about a pin 184 is adapted to rotate in a counterclockwise direction whenever the link 170 moves to the right. A coin return linkage is connected to depress the member 186 whenever a user operates the coin return to have money deposited in the machine returned, as is well known in the art. The member 186 is provided with a pin 188 adapted to be immobilized by the arm 190 of the bell crank 182 so that whenever a pull rod is being operated the coin return cannot be put into operation. The coin register shown in copending application, Serial No. 768,997 referred to above, is adapted to operate different columns at different prices. The parts comprising the lever 192, the spring 194, the member 196, the members 198, lever 200 are part of the price differential mechanism adapted to operate a change-maker forming part of the coin register. The member 202 which projects through crescent-shaped slot 204 coacts with the portion 206 of the lever 88 (shown in Figure 1) to accept the coins deposited in the coin register.

It will be seen that the arrangement is such that any of the knobs 36 may be pulled opposite the desired merchandise and limited motion is permitted to enable the coin register to sense whether or not the proper coins are in the coin register. If they are not, motion is stopped and no further action takes place. If the proper coins are in the coin register an unlocking action takes place permitting the pull rods to pass through their full amplitude of motion.

Referring now to Figures 5 and 6, a flexible steel tape 210 is wound about a spring reel 212. The tape extends downwardly in a guide channel formed by flanges 214. The lower end of the steel tape 210 carries a housing 216 secured thereto in any suitable manner. The housing carries for reciprocation therein a spring-pressed dog normally urged to the right, as viewed in Figure 5. The end of the dog terminates in a pin 218 abutting against the reciprocating member 60. If the pin 218 is pulled to the left by means of the knob 220, the tape may be pulled downwardly

unwinding about the spring reel 212. This action will successively strike the cranks 26 and tilt the shelves into the position shown in Figure 6 with the cranks 26 supported against the steel tape 210 in a position to support merchandise indicated by the reference numeral 209.

As the pull knob 36 is pulled the double cam member 52 moves forwardly, as viewed in Figure 5. Its first action is to pull the reciprocating member 60 downwardly against the action of spring 62. When the roller 68 slips by the end of the pivoted cam member 54 this member will occupy the position shown in Figure 5. As the member 52 returns, that is, when the pull rod is pushed back the roller 68 will be positioned underneath the pivoted cam plate 54 and the reciprocating member 60 will move down farther against the action of spring 62. The amplitude of motion is such that the lug 64 positioned just above the pin 218 will pass the pin moving it to the left against the action of its spring 217 and permitting it to ride past the lock 64. When the roller 68 passes the forward end of the pivoted cam plate 54 the spring 62 will pull the reciprocating member 60 upwardly until the roller 68 strikes the upper cam plate 56 to the position shown in Figure 5. This upward motion of the reciprocating member will move the steel tape upwardly clearing the crank 26 and permitting the shelf 20 to drop to the position shown in Figure 5, dumping the merchandise which strikes a delivery chute, part of which is formed by the curved plate 222 shown in Figure 5.

The action described above is repeated until the uppermost shelf is tripped. When this occurs the pin 218 of the spring dog will strike a lug 224 carried by the end of a reciprocal link 226 moving it upwardly through the action of the spring 62 carried by the member 60. The link carries a plate 228 at its lower end engaging a pin 230 carried by an empty locking lever 232. The end of lever 232 is formed with a hook 234 adapted to extend through a slot 233 formed in the housing 236. The lever 232 is pivotally mounted by pivot pin 231 upon reciprocating member 42 which is operated by pull rod 34 and adapted to move therewith whenever the double cam member 52 is operated. Normally, the vertically movable member 226 is in the lower position so that the locking lever 232 is rotated about its pivot 231 in a clockwise direction due to the weight of the pin 230 in order to bring it clear of the housing 236. When the parts are in the position shown in Figure 4 the pull rod cannot be operated except for a very short distance governed by the clearance between the hook 234 and the end of the slot formed in the housing 236. When the vertically reciprocating member 226 is lifted the empty locking lever 232 is rotated in a counterclockwise direction to bring the hook 234 into position in the slot formed in the housing 236. As the pull rod is operated the operating bar 32 moves forwardly and cams the member 240 downwardly. A bracket 242 formed of insulating material carries a light conducting member 244. The upper end 241 of the member 240 is adapted to wipe by and contact the conducting member 244 to complete a circuit lighting a small incandescent lamp serving as an empty signal to give the user notice that a particular column operated by the pull rod is depleted of merchandise. This wiping action occurs with every pull but the movement is so fast that the light merely flickers on as the pull rod is operated. The empty lock

arrangement, however, stops the parts at a point where the circuit is completed so that a pull of a pull rod will operate the empty signal and signal the user.

Referring now to Figure 8, we have shown another form of our invention in which the double cam plate 52 is eliminated and a single cam plate 55 is secured to the member 42 for operation with a pull rod. The cam plate 52 is formed with a cam slot 51 in which the roller 68 carried by the reciprocating member 60 is positioned. As a pull rod is pulled the member 42 moves to the right, as viewed in Figure 8, carrying with it the cam plate 55. The first action is to move the reciprocating member 60 downwardly through an amplitude sufficient to permit the spring pressed pin 218 to ride over the inclined lug 64 just above it on the reciprocating member 60. When the pull rod is pushed backward to its original position it will be cammed upwardly to the position at first occupied. This motion, however, will carry the lug 64 upwardly to its original position and in so doing will push the pin 218 upwardly, forcing the flexible steel tape 210 to move upwardly and freeing the crank 26 of the second shelf from the bottom, shown in Figure 8, permitting it to dump its merchandise. This action is repeated successively until all the shelves are dumped and the empty lock actuated by the pin 218 lifting the lug 224, as pointed out hereinabove.

In operation, let us assume that no coins are in the coin register and a pull rod is pulled. The pulling of one pull rod will lock all the other pull rods by the interlocking sliding wedges 39 actuated by the cam 41, as is well known to the art. The member 42 will move with the pull rod and move the operating rod 32 in the direction of the pull. The operating rod 32 is constrained to move in parallel motion by means of the gear segments 31 which are secured to the operating rod. The movement of the operating rod will pull the link 86 in Figure 1 to the left, rotating the bell crank 70 in a counterclockwise direction and lifting the link 102 until its end 101 butts the locking lug 118 carried by the locking lever 110. Here the action stops and nothing further occurs.

Let us now assume that a correct coin or coins are placed in the coin register. The action just described will again take place and the bell crank 70 will be rotated through a short distance in a counterclockwise direction carrying along the pins 76 and 78 which are secured to the bell crank 70. In Figure 1 the pin 76 moves to the left and the pin 78 moves upwardly. In Figure 3, to which reference is now made, the pin 76 moves to the right and pin 78 moves upwardly, carrying the cam 80 around in a clockwise direction, as shown by the arrow. This rocks the bell crank 134 in a counterclockwise direction moving the link 138 to the left and pivoting the lever 144 in a clockwise direction around its pivot 146. The upper end of the lever 144 will move to the right and carry the lower end of lever 156 to the right and with it the link 170, thus tensioning the spring 176 and all of the register slides 130 through the connecting linkages shown in Figure 3. At the same time the bell crank 182 will be rocked in a counterclockwise direction so that its arm 190 will immobilize the coin return member 186 through pin 188. Since there are the correct coins in the coin register one of the coin register slides 130 will be released depending upon the particular coins used. Its release will cause the coin register slide which is freed to move to the right, as

viewed in Figure 3, and to the left, as viewed in Figure 1, which motion will rock the unlocking lever 124 in a counterclockwise direction, carrying the lower end of the unlocking lever to the right against lug 122 which is carried by the locking lever 110 against the action of its spring 114, thus moving the locking lug 118 carried by the lower end of the locking lever clear of the path of travel of the end 101 of the locking link 102. This permits the bell crank 70 to continue to rotate and hence frees the pull rod 34 so that it may complete its full amplitude of travel. As soon as the toe 96 engages the first tooth 98 a user is constrained to complete the cycle and the machine cannot again be operated until the cycle is completed since all of the other pull rods are locked by the motion of one of them.

The operation of the pull rod will cause the reciprocating member 60 to reciprocate, that is, to be pulled downwardly and snapped upwardly by the spring 62 in the form of the invention shown in Figure 5, or to be pulled downwardly and pushed upwardly by the cam slot 51 in the form of the invention shown in Figure 8. The movement of the member 60 in the downwardly direction is of sufficient amplitude so that one of the lugs 64 just above the pin 218 will ride downwardly past the pin and engage the bottom of it, the spring 217 permitting the pin to move to accommodate this motion. The upward motion of the member 60 will move the flexible steel tape 210 upwardly to move it clear of the bottommost crank 26 which is in engagement therewith, thus allowing the freed shelf to pivot to dump its merchandise.

At the same time the merchandise is being delivered on the return motion of the plunger, the lever 88, shown in Figure 1, will pivot in a counterclockwise direction permitting its curved portion 206 to wipe by the member 202 shown in Figure 3 to accept the money and remove it from the coin register so that additional coins will have to be deposited before the cycle can be again performed.

After the uppermost shelf is tripped the empty lock will function so that a pull knob 36 opposite an empty column cannot be operated and the user must select another column containing merchandise.

The shelves may be spaced with any desired spacing depending upon the size of the merchandise to be vended. If candy bars are being vended, and they are small, columns may be constructed with shelves positioned closely adjacent one another. Different cam plates and different reciprocating members are used for different spacing of shelves as the cam plate and reciprocating member must be correlated with the shelf spacing.

It will be seen that we have accomplished the objects of our invention. We have provided an automatic merchandising machine adapted to vend articles which cannot be stacked. Our machine is simple in construction and is operable in a convenient and expeditious manner. When a column is empty all of the shelves can be rapidly moved to a horizontal position by pulling the pin 218 to the left through the knob 220 and then pulling the steel tape downwardly quickly pivoting the shelves to their merchandise supporting position in rapid succession. Our machine is adapted to be used for automatic merchandising of candy bars, and each candy bar will be separately supported without the danger of being crushed or deformed by contact

with another candy bar. A large number of shelves may be used within a given space so that we can produce a machine having a large capacity. Our machine is flexible in design, simple and inexpensive in construction and certain in its operation.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention. It is therefore to be understood that our invention is not to be limited to the specific details shown and described.

Having thus described our invention, what we claim is:

1. An automatic merchandising machine including in combination a frame, a plurality of shelves adapted to support merchandise, means for pivotally mounting said shelves on said frame in vertically spaced position, each of said shelves being pivoted along an axis displaced from the longitudinal center line thereof, each of said shelves having a crank carried thereby and adapted to pivot therewith, an elongated member, means for mounting said elongated member for vertical movement adjacent the shelf cranks and adapted to contact the same to pivot the shelves to horizontal position, means for stepping said elongated member successively free of the shelf cranks whereby to permit the shelves to pivot to dump merchandise supported thereon, and coin controlled actuating means for operating said stepping means.

2. An automatic merchandising machine including in combination a frame, a plurality of vertically spaced shelves pivotally mounted on said frame for movement around an axis adjacent one side thereof, shelf positioning means carried by each of said shelves, a vertically movable member mounted for movement adjacent said shelf positioning means and adapted to contact therewith to pivot the shelves to substantially horizontal position, a reciprocating member mounted for movement adjacent said vertically movable member, coacting means carried by said movable member, and said reciprocating member adapted to move the vertically movable member stepwise free of the shelf positioning means of successive shelves, and coin controlled means for operating said reciprocal member.

3. An automatic merchandising machine as in claim 2 in which said shelf positioning means comprise cranks adapted to pivot with said shelves.

4. An automatic merchandising machine as in

claim 2 in which said vertically movable means comprises a flexible elongated tape.

5. An automatic merchandising machine as in claim 2 in which said coacting means comprises a spring pressed pin carried by the vertically movable member and a plurality of lugs carried by the reciprocating member.

6. An automatic merchandising machine as in claim 2 in which said coin controlled operating means comprises a pull member, a cam carried by said pull member and a cam follower carried by said reciprocating member.

7. An automatic merchandising machine including in combination a frame, a plurality of columns of vertically positioned shelves carried by said frame, means for pivoting said shelves adjacent their sides, shelf positioning means carried by each of said shelves, a plurality of flexible elongated members positioned for vertical movement adjacent said shelf positioning means and adapted to coact therewith to place the shelves in substantially horizontal position, a plurality of reciprocating members positioned adjacent respective elongated flexible members, coacting means carried by said reciprocating members and said flexible members adapted to engage to move the respective flexible members upwardly free of coaction with successive shelf positioning means, cam followers carried by respective reciprocating members, cams adapted to actuate respective cam followers to operate respective reciprocating members, locking means adapted to immobilize all of the cams, pull rods for actuating respective cams, and coin controlled means for freeing the locking means whereby a pull rod opposite its respective column may be actuated to move the reciprocating member to dump the lower shelf in horizontal position.

8. An automatic merchandising machine as in claim 7 in which each of said cams is provided with a locking means adapted to prevent the operation of the same, and means actuated by said flexible member at a predetermined position in its travel for moving said locking means into locking position.

CHRISTIAN GABRIELSEN.
HRAND VORPERIAN.
